UNITED STATES PATENT OFFICE

164,112

MILK BOTTLE

Norman A. Henderson, Albany, N. Y.

Application September 28, 1949, Serial No. 5,200

Term of patent 3½ years

(Cl. D58—6)

To all whom it may concern:

Be it known that I, Norman A. Henderson, a citizen of the United States, residing at Albany, county of Albany and State of New York, have invented a new, original, and ornamental Design for Milk Bottle, of which the following is a specification, reference being had to the accompanying drawing, forming a part thereof in which—

Fig. 1 is a front elevational view of a bottle showing my new design; and

Fig. 2 is a fragmentary cross section in the plane 2—2 of Fig. 1.

I claim:

The ornamental design for a milk bottle, as shown.

NORMAN A. HENDERSON.
